CLAIM

We claim the ornamental design for a dashboard vent mount for an electronic device, as shown and described.

DESCRIPTION

FIG. 1 is a rear perspective view of a dashboard vent mount for an electronic device;

FIG. 2 is a front perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left elevational view thereof; and,

FIG. 8 is a right elevational view thereof.

Broken lines are used to illustrate unclaimed details the dashboard vent mount for an electronic device; broken lines are not part of the claimed design.

1 Claim, 8 Drawing Sheets
